UNITED STATES PATENT OFFICE.

FREDERICK R. LONG, OF BERWICK, PENNSYLVANIA, ASSIGNOR TO AMERICAN CAR AND FOUNDRY COMPANY, OF NEW YORK, N. Y., A CORPORATION OF NEW JERSEY.

DEVICE FOR SPRAYING PAINT AND OTHER LIQUIDS.

Application filed January 2, 1920. Serial No. 348,732.

To all whom it may concern:

Be it known that I, FREDERICK R. LONG, residing at Berwick, Columbia County, State of Pennsylvania, and being a citizen 5 of the United States, have invented certain new and useful Improvements in Devices for Spraying Paint and Other Liquids, of which the following is a full, clear, and exact description, such as will enable others 10 skilled in the art to which it appertains to make and to use the same, reference being had to the accompanying drawings, which illustrate the preferred form of the invention, though it is to be understood that the 15 invention is not limited to the exact details of construction shown and described, as it is obvious that various modifications thereof within the scope of the claims will occur to persons skilled in the art.

20 In said drawings:

Figure 1 is a longitudinal vertical section through the device illustrating the parts in their normal or inoperative position;

25 Figure 2 is a front elevational view of the apparatus;

Figure 3 is a vertical section taken on line 3—3, Fig. 1, looking in the direction indicated by the arrow, through the rear chamber of the sliding valve;

30 Figure 4 is a similar view taken on line 4—4 of Fig. 1 looking in the direction indicated by the arrow and showing the relative positions of the parts carried by the sliding valve in the vicinity of the air inlet 35 in the valve;

Figure 5 is a vertical section taken on line 5—5 of Fig. 1 looking in the direction indicated by the arrow and toward the nozzle of the device;

40 Figure 6 is a section similar to Figure 1 showing the slide valve slightly advanced with its air port in partial communication with the air supply and its liquid port still closed; and

45 Figure 7 is a view similar to Figure 6 with the slide valve further advanced and both air and liquid ports registered with the ports leading to respective sources of supply.

50 The object of the invention is to provide a device for spraying paint or other liquid for use in painting or finishing operations.

The preferred embodiment may be in the form illustrated in the drawings showing a 55 casing or framing made up of any suitable

material, preferably aluminum on account of its light weight. Such framing is shaped for convenient handling and comprises a number of compartments, the uppermost of which forms a housing 10 for the reciprocating parts of the device while the portion depending from the housing serves as a handle 11 for the apparatus and is chambered to provide conduits or compartments 12 and 13 leading respectively to the sources 60 of air and liquid supply. A partition 14 separates compartments 12 and 13 from the interior of housing 10, communication between said conduits and housing being established through the medium of ports 15 65 and 16 the opening and closing of which are controlled by means of a unitary sleeve valve hereinafter to be described, said ports leading respectively to air and liquid conduits. Within the housing 10 is fitted a 70 wearing sleeve or bushing 17 designed to receive the sliding valve referred to and also provided with port holes forming continuations of ports 15 and 16.

Reciprocating within the housing is a 80 slide valve 18 acting as a unit to control both air and liquid ports 15 and 16 respectively and to successively open and close said ports, the relative positions of the ports being such that while the opening 85 and closing of the same are effected successively, in one position of the slide valve both ports are open to insure simultaneous flow of air and liquid and are closed upon return of the slide valve to normal position. This result is achieved by means of 90 slide valve ports 19 and 20 so spaced from each other and positioned relatively to respective ports 15 and 16 in the housing that during the progress of the slide valve to 95 open position, port 19 will first enter into communication with port 15 of air conduit 12 as shown in Figure 6 and a substantial flow of air established, after which port 20 of the valve will connect with port 16 of 100 liquid conduit 13 as shown in Figure 7 and permit simultaneous flow of air and liquid. A reverse movement of the slide valve will first close liquid ports 16 and 20 as indicated in Figure 6 and finally the air ports 105 15 and 19 thus insuring complete evacuation of all liquid remaining in the valve after closing of liquid ports, and a further movement in the same direction will carry the slide valve to the position shown in Fig- 110

ure 1 in which all communication with the source of supply is cut off as indicated.

For the purpose of controlling the supply and direction of flow of air and liquid, the 5 slide valve is chambered as shown at 21 and 22 indicating respectively the air and liquid compartments of the valve. These slide valve compartments communicate with the sources of air and liquid supply through the 10 medium of ports 15-19 and 16-20, respectively, and open to the atmosphere through air discharge tube 23 and liquid discharge tube 24 threaded respectively into chambers 21 and 22. The tubes are concentrically arranged within the valve and reciprocate therewith as a unit and terminate in a nozzle 25 fashioned to spray the liquid issuing therefrom. Within the liquid tube 24 and extending along its center is arranged a 20 rod 26 threaded into the rear wall 27 of liquid chamber 22 and provided with a choking head 28 within the nozzle opening designed to reduce the mass of the liquid at that point so as to be more readily broken 25 up into spray formation. The choking head is slotted at 29 to facilitate adjustment of rod 26 to regulate the supply of liquid at the nozzle. To keep choking head 28 properly centered within the nozzle, the rod 26 30 is supported intermediate its ends by any suitable means which may take the form of a separate spider 26^a encircling the rod and fitted within liquid tube 24.

The nozzle end of the housing is closed 35 by a screw cap 30 perforated to receive the air tube 23 and adapted to confine the reciprocating parts within housing 10. For the purpose of restoring the slide valve to normal or inoperative position a spring 31 40 is employed to expand against abutments on the screw cap 30 and sleeve valve 18 and operates to yieldingly oppose any force tending to move the slide valve from its normal position.

45 Propelling mechanism for projecting the nozzle is mounted on the outside of the casing and takes the form of a trigger 32 fulcrumed at 33 to a bracket 34 on the casing and connected to the reciprocating member 50 in any suitable manner. In the drawings, such connection is shown in the form of a pin 35 removably mounted in the trigger 32 and lugs 36 on the air tube 23. Where conditions are such as to insure against interruption in spraying operations over extended 55 intervals of time, the slide valve 18 may be set and locked at any stage of its range of movement to complete open position, by means outside of the casing and independent 60 of the trigger mechanism, thereby relieving the operator of the strain required in keeping the trigger pressed back against the force exerted by the spring 31. A desirable form of locking and setting means is shown 65 in the drawings comprising a set-screw 37

mounted at the rear of casing 10 and entering the interior thereof for engagement with the rear wall 27 of the slide valve. In Figure 1 the set-screw 37 is set to the normal or inoperative position of the slide valve and 70 is shown impinging the rear wall 27 of the valve to limit the rearward movement thereof under the action of spring 31. The action of the slide valve is not influenced by the set screw in this position, but should the 75 screw be advanced to a point where it would prevent rearward movement of the slide valve beyond positions in which the air ports alone are open, or both air and liquid ports as shown respectively in Figures 6 and 7, air 80 spraying operations alone or air and liquid spraying together may be carried out without pressing upon trigger 32. The set-screw 37 may be locked in its complete advanced position indicated in dotted lines in Figure 85 7 or in any other position desired by means of a lock-nut 38 threaded on the set-screw and holding same against rotation. Provision against leakage is made in the joint between the slide valve 18 and bushing 17 90 by means of packing rings 39 fitted to the slide valve on opposite sides of the air and liquid ports. Leakage within the slide valve is guarded against by the threaded joints 40 and 41 on the air and liquid tubes, respectively. In order to compress the packing rings 39 in the process of assembling slide valve and housing, and to permit the packing rings to enter the housing readily the front end of the bushing 17 is beveled or 100 tapered as shown at 42.

In operation, the air and liquid are supplied to the device through their respective conduits 12 and 13 in the handle 11 of the apparatus. Pressure of the finger on trigger 32 will propel slide valve 18 and parts carried thereby and cause same to be projected as a unit until said valve has progressed to a point where air ports 15 and 19 register when the air will commence to 110 flow through conduit 12, ports 15 and 19 to the valve interior thence through air tube 23 to nozzle 25 to the atmosphere. After the current of air is established, further projection of the valve 18 will cause registration 115 of liquid ports 16 and 20 bringing about the flow of liquid through conduit 13, to valve interior thence through liquid tube 24, to nozzle 25, where it meets with and is broken up by the air issuing out of the air tube, the 120 course taken by the air and liquid currents follows the direction indicated by arrows in Figures 1, 6 and 7 of the drawings.

Under the influence of spring 31, the slide valve will move in the reverse direction to normal or inoperative position at a certain stage of which movement, liquid ports 16 and 20 will be first to close, cutting off the liquid supply and permitting the already established air current to completely 130

clear the apparatus of all liquid remaining in the casing and valve thereby keeping the nozzle clear of said liquid which if allowed to remain would congeal and harden in the 5 nozzle. From this it follows that a further rearward movement would carry the valve to its normal or inoperative position in which the air ports also will be closed.

From the foregoing it will be clear that 10 the device is automatic in successively opening and closing the air and liquid ports, and that the valve will operate to open the air ports first and close them last; that the air and liquid tubes, together with choking rod 15 26, are carried by the slide valve and move with same as a unit; that all of the valve movements are directed by a single mechanism positioned wholly outside the casing and reciprocating parts.

20 What I claim is:

1. In mechanism of the class described, the combination with a casing comprising a valve housing and air and liquid compartments, of a reciprocatory valve within said 25 housing adapted to establish communication with said air and liquid compartments and a spray nozzle adapted to be reciprocated in unison with said valve.

2. In mechanism of the class described, 30 the combination with a casing comprising a valve housing and air and liquid compartments, of a reciprocatory valve within said housing adapted to successively establish communication with said air and liquid 35 compartments and a spray nozzle adapted to be reciprocated in unison with said valve.

3. In mechanism of the class described, 40 the combination with a casing comprising a valve housing and air and liquid compartments, of a reciprocatory sleeve valve within the housing, air and liquid tubes carried by said valve, said valve being adapted to successively establish communication between said tubes and compartments.

4. In mechanism of the class described, 45 the combination with a casing comprising a valve housing and air and liquid compartments, of a chambered reciprocatory 50 valve within the housing, concentrically arranged air and liquid tubes carried by the valve and opening into said chambers, said valve being adapted to establish communication between said tubes and compartments.

5. In mechanism of the class described, 55 the combination with a casing comprising a valve housing and air and liquid compartments, ports in the housing opening into said compartments, of a reciprocatory valve in said housing adapted to successively open and close said ports and a spray nozzle carried by said valve.

6. In mechanism of the class described, 60 65 the combination with a casing comprising

a valve housing, and air and liquid compartments, ports in the housing opening into said compartments, of a reciprocatory valve in said housing adapted to successively open and close said ports, discharge tubes carried by said valve and projecting beyond said housing, and means for controlling the movements of said valve mounted outside the casing and connected to one of said tubes.

7. In mechanism of the class described, 70 a reciprocatory valve comprising a hollow sleeve having air and liquid receiving chambers, concentrically arranged tubes carried by the valve and opening into said chambers, a housing for said valve connected with sources of air and liquid supply, and means outside of said housing for moving said valve to establish communication between the chambers of said valve and respective 75 sources of supply.

8. In mechanism of the class described, 80 a reciprocatory valve, a housing for the valve, said housing being connected with sources of air and liquid supply, said valve being adapted to establish communication 85 between said housing and sources of supply and a spray nozzle carried by said valve.

9. In a mechanism of the class described, 90 a reciprocatory valve having air and liquid receiving chambers, a housing for said valve, concentrically arranged discharge tubes extending into the housing and moving with said valve, the chambers of the valve opening respectively into one of said tubes, 95 sources of air and liquid supply, means outside of said housing connected with one of said tubes for moving said valve in a direction adapted to establish communication between said tubes and sources of supply, and 100 resilient means within the housing operating to restore said valve to inoperative position.

10. In a mechanism of the class described, 105 a valve housing, a reciprocatory valve, a removable cap for said housing provided with an opening, a member carried by said valve and extending through the opening in said cap, a spray nozzle carried by said member, controlling means outside of said housing connected with said member for moving said valve in one direction, and resilient means within the housing operating to restore said valve to inoperative position.

11. In a mechanism of the class described, 110 a casing comprising a valve housing and air and liquid compartments, ports in the housing opening into said compartments, a reciprocatory valve within the housing carrying air and liquid tubes and adapted to 115 successively establish communication between said tubes and respective compartments in one direction of movement and successively close the ports upon a reverse movement thereof.

12. In mechanism of the class described, a casing comprising a valve housing and air and liquid compartments, a reciprocatory valve within said housing adapted to 5 successively establish communication with said compartments, a spray nozzle carried by said valve, and valve reciprocating mechanism outside of said casing.
13. In mechanism of the class described, 10 a casing comprising a valve housing and air and liquid compartments, a reciprocatory valve within said housing adapted to successively establish communication with said compartments, valve reciprocating mechanism outside of said casing, and valve setting means.
14. In a mechanism of the class described, a casing having ports therein, a chambered valve adapted to connect said ports and 20 chambers, discharge tubes carried by said valve and connected to said chambers and a spray nozzle carried by said tubes.
15. In a mechanism of the class described, a casing having ports therein, and a valve 25 having a plurality of chambers adapted to connect said ports and chambers and con-
- centric discharge tubes extending from said chambers.
16. In a mechanism of the class described, a casing having ports therein, a valve having a plurality of chambers adapted to connect said ports and chambers and discharge tubes connected to said chambers, operating means for said valve, means adapted to return said valve to its inoperative position and means adapted to prevent the return of the valve to its inoperative position. 30
17. In a mechanism of the class described, a casing having air and liquid supply ports 40 therein, a valve having air and liquid chambers adapted to connect said chambers to said ports and concentric discharge passages extending from said chambers and a spray nozzle carried by said valve. 45

In witness whereof I have hereunto set my hand in the presence of two witnesses.
